UNITED STATES PATENT OFFICE

103,539

DESIGN FOR AN ASH TRAY

Robert W. Moore, Camden, N. J.

Application September 15, 1936, Serial No. 64,862

Term of patent 14 years

To all whom it may concern:

Be it known that I, Robert W. Moore, a citizen of the United States, residing in Camden, county of Camden, State of New Jersey, have invented a new, original, and ornamental Design for an Ash Tray, of which the following is a specification, reference being had to the accompanying drawing, which forms a part thereof:

Fig. 1 is a top plan view of an ash tray showing my new design; and

Fig. 2 is an edge view thereof.

I claim:

The ornamental design for an ash tray as shown.

ROBERT W. MOORE.
